RADIO TELEGRAPH RECEIVING SYSTEM

Percival D. Lowell, Chevy Chase, Md., assignor to
 Radio Corporation of America, New York,
 N. Y., a corporation of Delaware

Application July 25, 1933, Serial No. 682,132

9 Claims. (Cl. 250—8)

My invention relates broadly to radio receiving apparatus and more particularly to apparatus for the reception of continuous wave radio telegraph code signals.

- 5 One of the objects of my invention is to provide a circuit arrangement for a continuous wave radio telegraph receiving system having means for stabilizing the tone frequency of the received signals.
- 10 Another object of my invention is to provide an improved superheterodyne type of radio receiving circuit for the reception of continuous wave telegraph signals having means for stabilizing the tone frequency of the reproduced telegraphic signals.

15 Still another object of my invention is to provide a circuit arrangement for superheterodyne type of radio receiving systems wherein the high frequency oscillator which coacts with the first detector is continuously modulated at a constant frequency adapted to be selectively impressed upon the audio frequency signal output circuit in accordance with the received telegraphic signals.

20 Still another object of my invention is to provide a continuous wave superheterodyne type of radio telegraph receiving system including a high frequency oscillator arranged to coact with a first detector in combination with a source of audio frequency modulating energy which is adapted to be transferred through the intermediate frequency amplifier, second detector and audio frequency amplifier of the superheterodyne receiver in accordance with the telegraphic signals which are received for thereby determining the character of the audio frequency signaling energy which is delivered to the audio frequency signal output circuit.

25 A further object of my invention is to provide a circuit arrangement for the selective reception of radio telegraph signals through a superheterodyne receiving circuit with minimum interference from static or undesired signals in which a source of audio frequency signaling energy at the receiver is rendered effective upon a preselector circuit of an audio frequency amplification system which tends to reject undesired frequencies and static disturbances.

30 A still further object of my invention is to provide a selective continuous wave radio telegraph receiver of the superheterodyne type wherein the high frequency oscillator which coacts with the first detector is modulated at a predetermined audio frequency rate to which the audio frequency amplification system is selectively tuned whereby the incoming telegraphic signals effect the trans-

fer, through the intermediate frequency amplifier and second detector to the audio frequency amplification system, of that frequency to which the audio frequency amplification system is selectively adjusted.

35 Other and further objects of my invention reside in the selective continuous wave radio telegraph signal receiving system as set forth more fully in the specification hereinafter following by reference to the accompanying drawing which 10 diagrammatically illustrates the system of my invention.

40 In the circuits now commonly used in radio telegraphy it is customary to employ either an oscillating detector or a separate oscillator for the purpose of generating oscillations to beat with the incoming signal waves, thereby rendering the incoming code signals audible to the ear or useful in operating a recorder or printer. It is the purpose of my invention to provide a more stable, 15 simpler and more easily adjusted method of rendering the continuous wave signals audible than that obtainable in the usual beat frequency oscillator type of circuit. My invention of necessity requires a receiver of the superheterodyne 20 type in which an oscillator is employed to convert the incoming signal frequency to a frequency of a different value. I have found that if the oscillator in a superheterodyne receiving system be continuously modulated at a constant audio frequency, this audio frequency will not pass through the intermediate frequency amplifier, second detector and audio frequency amplifier unless a continuous wave incoming signal is also present. In 25 other words, an incoming continuous wave signal when it reaches the oscillator, besides being converted to a different frequency, also becomes modulated at the audio frequency. The converted and modulated signal will then pass through the intermediate frequency amplifier, second detector 30 and audio frequency amplifier and the dots and dashes will be reproduced at the frequency of the audio modulation. The system of my invention is rendered especially selective by reason of the 35 peaked characteristic of the audio frequency amplifier at a certain frequency. I may also employ an audio frequency amplifier having a sharp band pass characteristic for the purpose of eliminating interference or reducing the response of the receiver to static disturbances. The audio frequency 40 response characteristic of the audio frequency amplifier system is selected to correspond to the modulation and frequency of the high frequency oscillator, thereby rejecting undesired signal 45

55

quencies and reducing the response to static disturbances.

Referring to the drawing, I have shown a superheterodyne receiver circuit comprising the 5 antenna circuit 1, the radio frequency amplifier 2, the first detector 3, the oscillator 4, the intermediate frequency amplifier 5, second detector 6, audio frequency amplifier 7, and audio frequency output circuit 8 which connects to a signal 10 indicating device, recorder or printing mechanism. The oscillator 4 is modulated by the source of audio voltage 10 which is introduced into the oscillator circuit through the coupling transformer 9. The coupling transformer 9 includes a primary winding 11 connected with the source of audio voltage 10 and a secondary winding 12 connected in series with the input circuit of the oscillator between the biasing resistor 14 and the lower terminal of the tuned circuit 15. 15 The oscillator includes the coupling coil 16 in the output circuit thereof inductively related to the inductance of the tuned circuit 15 in the input circuit of the oscillator. The high frequency oscillations generated by oscillator 4 are impressed upon the circuit of the first detector 3 by the electro-magnetic coupling between oscillator coils 15, 16 and the tuned grid circuit of the detector 3. The source of potential 18 supplies plate excitation for all of the electron tubes. I 20 have illustrated the indirectly heated type of electron tube employed in the oscillator and throughout the several stages of the receiver. The audio frequency amplification system which has been represented for purposes of explaining 25 my invention, has a single amplifier stage, preceded by a preselector circuit which I have designated at 19. The preselector circuit includes the secondary winding audio frequency transformer 20 with a condenser 21 connected in shunt thereto and adjusted to the audio frequency produced by the source of audio voltage 10. Inasmuch as the tuned circuit 19 is selectively responsive to the frequency of the modulator 10, interfering frequencies and static effects produce a 30 minimum effect upon audio frequency amplification system 7. The tuned circuit 19 is matched to the frequency of the modulator 10. The frequency of the modulator 10 will not pass through the intermediate amplifier 5 or the second detector 6 to the transformer 20 and preselector circuit 19 unless a continuous wave incoming signal is also present. When a continuous wave incoming signal reaches the oscillator, the beat or intermediate frequency thereby produced is impressed upon the intermediate frequency amplifier 5 and at the same time the modulation from source 10 is transferred through the intermediate frequency amplifier 5 to the second detector 6, audio frequency transformer 20 to pre- 35 selector circuit 19 and then to audio frequency amplifier 7 for operation of the indicating device or printing mechanism which may be connected to the audio frequency output circuit 8.

The condenser 22 connects across the secondary winding 12 and across the biasing resistor 14 and provides a radio frequency path for the oscillations generated by oscillator 4 around the source of audio frequency oscillations. That is to say, the high frequency path from the end of tuned circuit 15 to the cathode of tube 4 is closed through condenser 22 while allowing audio frequency oscillations to be impressed from source 10 upon the input circuit of the oscillator 4.

I have found the continuous wave receiving 75 system of my invention highly practical in its

operation. I have used the circuit in the operation of automatic printers by radio with highly successful results over substantial distances. While I have described my invention in one of its preferred embodiments, I desire that it be understood that modifications may be made and that no limitations upon my invention are intended other than are imposed by the scope of the appended claims.

What I claim as new and desire to secure by 10 Letters Patent of the United States is as follows:

1. A continuous wave radio telegraph receiving system comprising a superheterodyne receiving circuit including a first detector, a high frequency oscillator connected therewith, an intermediate 15 frequency amplifier connected with said first detector, a second detector connected with said intermediate frequency amplifier, a preselector circuit connected with the output of said second detector, an audio frequency amplifier system 20 connected with said preselector circuit and a source of audio frequency oscillation connected with said high frequency oscillator, said preselector circuit being tuned to select the frequency of said source of audio frequency oscillation. 25

2. A continuous wave radio telegraph receiving system comprising a superheterodyne receiving circuit including a first detector, a high frequency oscillator connected therewith, an intermediate frequency amplifier connected with said first detector, a second detector connected with said intermediate frequency amplifier, a preselector circuit comprising a tunable condenser and a winding of an audio frequency transformer connected with the output of said second detector, 30 an audio frequency amplifier system connected with said preselector circuit and a source of audio frequency oscillation connected with said high frequency oscillator for continuously modulating the oscillations impressed on said first detector 35 at an audio rate, the frequency adjustment of said preselector circuit being matched to correspond to the frequency of said source of audio frequency oscillations. 40

3. A continuous wave radio telegraph receiving system comprising a superheterodyne receiving circuit including a first detector, a high frequency oscillator connected therewith, an intermediate frequency amplifier connected with said first detector, a second detector connected with said intermediate frequency amplifier, a preselector circuit connected with the output of said second detector, an audio frequency amplifier system connected with said preselector circuit, a source of audio frequency oscillation connected between the grid and cathode of said high frequency oscillator for continuously modulating the oscillations impressed on said first detector at an audio rate, and a radio frequency by-pass condenser also connected to said grid and cathode, said preselector circuit being tuned to select the frequency of said source of audio frequency oscillation. 50

4. A continuous wave radio telegraph receiving system comprising a superheterodyne receiving 65 circuit including a first detector, a high frequency oscillator connected therewith, an intermediate frequency amplifier connected with said first detector, a second detector connected with said intermediate frequency amplifier, a preselector circuit comprising a variable condenser and an inductance connected with the output of said second detector, an audio frequency amplifier system connected with said preselector circuit, a source of plate supply for said high frequency 70 oscillator. 75

- 5   frequency oscillations, said source supplying energy for the plate circuits of said first and second detectors and said intermediate and audio frequency amplifiers, a source of audio frequency oscillation connected between the grid and cathode of said high frequency oscillator for continuously modulating the oscillations impressed on said first detector at an audio rate, and means for bypassing the high frequency oscillations generated by said oscillator around said source of audio frequency oscillations, said condenser of said preselector circuit being capable of adjusting said circuit to the frequency of said audio frequency source.

10   5. A continuous wave radio telegraph receiving system comprising a superheterodyne receiving circuit including a first detector, a high frequency oscillator having a tuned circuit connected at one end to the grid of the oscillator, a connection between the other end of said tuned circuit and the cathode, a transformer having the secondary winding thereof disposed in said connection, a source of audio frequency oscillations connected with the primary winding of said transformer, an intermediate frequency amplifier connected with said first detector, a second detector connected with said intermediate frequency amplifier, a common source of plate supply for all stages of said receiving system, a preselector circuit connected with said second detector, and an audio frequency amplification system connected with said preselector circuit, and means for adjusting said preselector circuit to the frequency of said audio frequency source.

15   6. A continuous wave radio telegraph receiving system comprising a superheterodyne receiving circuit including a first detector, a high frequency oscillator having a tuned circuit connected at one end to the grid of the oscillator, a connection between the other end of said tuned circuit and the cathode, a transformer having the secondary winding thereof disposed in said connection, a source of audio frequency oscillations connected with the primary winding of said transformer, an intermediate frequency amplifier connected with said first detector, a second detector connected with said intermediate frequency amplifier, a preselector circuit connected with said second detector, an audio frequency amplification system connected with said preselector circuit, means for adjusting said preselector circuit to the frequency of said audio frequency source, and means connected across the secondary winding of said transformer forming a closed path for the high frequency oscillations generated by said oscillator around said source of audio frequency oscillations.

20   7. A continuous wave radio telegraph receiving system comprising a superheterodyne receiving circuit including a first detector, a high frequency oscillator having a tuned circuit connected at one end to the grid of the oscillator, a connection between the other end of said tuned circuit and the cathode, a transformer having the secondary winding thereof disposed in said connection, a source of audio frequency oscillations connected with the primary winding of said transformer, an intermediate frequency amplifier connected with said first detector, a second detector connected with said intermediate frequency amplifier, a preselector circuit connected with said second detector, an audio frequency amplification system connected with said preselector circuit, means for adjusting said preselector circuit to the frequency of said audio frequency source, and a condenser connected across the secondary winding of said transformer for forming a closed path for the high frequency oscillations generated by said oscillator around said source of audio frequency oscillations.

25   8. In a superheterodyne high-frequency signal receiving system, in combination, a first detector, a local oscillator coupled with the first detector for supplying an oscillation to beat with an incoming continuous wave signal to produce an intermediate frequency wave, an auxiliary oscillator adapted to modulate said local oscillator at a constant audio frequency, said intermediate frequency wave being thereby likewise modulated and having besides the character of the incoming continuous wave signal, an intermediate frequency amplifier coupled with said first detector, a second detector, and an audio frequency amplifier peaked at the said audio frequency.

30   9. In a superheterodyne high-frequency continuous wave signal receiving system, in combination, a first detector, a local oscillator, an intermediate frequency amplifier, a second detector, means for modulating the current in said intermediate frequency amplifier at a constant audible frequency and in the character of the received signal, said audible frequency modulation being detected in said second detector in the character of the received signal, and an audio frequency filter and a peaked audio frequency amplifier for selectively amplifying said modulation.
